UNITED STATES PATENT OFFICE.

GLEN R. WESTCOTT AND GUY E. WESTCOTT, OF LOS ANGELES, CALIFORNIA.

DESIGN FOR A CLIP FOR PENCILS, FOUNTAIN-PENS, OR SIMILAR ARTICLES.

51,564.

Specification for Design.

Patented Dec. 11, 1917.

Application filed May 15, 1917. Serial No. 168,891. Term of patent 3½ years.

To all whom it may concern:

Be it known that we, GLEN R. WESTCOTT and GUY E. WESTCOTT, citizens of the United States, residing at Los Angeles, county of Los Angeles, State of California, have invented a new, original, and ornamental Design for Clips for Pencils, Fountain-Pens, or Similar Articles, of which the following is a specification, reference being had to the accompanying drawing, forming a part thereof.

Figure 1 is a front elevation of the clip, showing our new design.

Fig. 2 is a plan view thereof.

We claim:

The ornamental design for a clip for pencils, fountain pens, or similar articles, as shown.

GLEN R. WESTCOTT.
GUY E. WESTCOTT.
